METHOD OF ATTACHING A POST TO A
TOP-LIFTRobert W. Chandler, Worcester, Mass., assignor
to Fitz-On Sales Corporation, Worcester, Mass.,
a corporation of Massachusetts

Application July 23, 1934, Serial No. 736,498

4 Claims. (Cl. 12—147)

The present invention relates to detachable top lifts having an attached post for reception in a cooperating socket, and to a method of producing the same in a manner to provide a uniform relationship between the post and receiving socket.

The purpose of the invention is to provide a post of simple and economical construction which is uniform in its characteristics, and which may be readily inserted and caused to frictionally engage within a receiving socket to retain the top lift against dislodgment and turning movement with respect to the heel.

With this and similar objects in view, I propose to form a post of generally triangular cross-section having a base portion from the opposite edges of which extend toward one another two inclined and resilient wall portions spaced apart at their adjacent outer edges to permit yielding 20 of the walls toward and from one another with a consequent spring action. The post is conveniently blanked from a single sheet by folding along longitudinally parallel lines, and is beveled or cut away at the entering ends of the resilient 25 wings to facilitate compression of the wing upon entering the socket. In addition to the provision of this type of post which has been found to satisfactorily serve its purpose, I provide a method by which the post may be sized to a uniform 30 cross-section with respect to the socket in which it is received.

Ordinarily in this type of construction the post is permanently assembled with the top lift by the assembly of the two members in a cavity mold, 35 and thereafter uniting and clinching the prongs of the post within the top lift through pressure. If the post fits the cavity of the mold so closely as to be reduced to a predetermined size thereby, it is extremely difficult and laborious to assemble 40 it. If it does not fit the cavity of the mold precisely, variations in the shape and contour of the post interfere with its proper fit in the receiving socket.

According to the present method I propose to 45 provide a post-receiving mold cavity which fits the post loosely and permits the latter to be dropped therein by gravity. Subsequent to the assembly of the post in the cavity the resilient wings of the post are engaged adjacent the attaching end by sizing and locating members which 50 move the wings to a predetermined position to create an invariable relationship and fix the cross-section of the post. In this invariable relationship of the wings the post is permanently 55 assembled with the top lift and clinched thereto,

and upon removal from the mold cavity the top lift is permanently assembled in predetermined relation with the post, and the latter has a definite and unvarying cross-section which permits of its uniform reception within the receiving 5 socket.

Referring particularly to the illustrated embodiment of the invention, Fig. 1 illustrates the blank from which the post is formed; Figs. 2 and 3 are views in elevation of the finished post; Fig. 4 is an illustration of a top lift with attached post received within a heel; Fig. 5 is a cross-section of the post on the line 5—5 of Fig. 2; and Figs. 6 and 7 are views showing longitudinal sections, in elevation and plan, respectively, of the 15 molding cavity within which the post is located, and the means for sizing the post prior to its assembly to the top lift.

The post shown in the illustrated embodiment of the invention is produced from a blank 10, 20 having points 12 at one end and beveled portions 14 at the opposite end. When the blank is folded along the dot and dash lines 16 into the triangular form shown in Figs. 2 and 3, the lower end is offset to produce attaching prongs 18, as 25 will be evident. The beveled portions 14 are formed upon the resilient wings which are indicated at 20. The rear portion 22 forms the base of the triangle and the portions 20 the resilient inclined sides. It will be noted that these sides 30 at their outer adjacent edges do not touch, and have capacity for some yielding movement.

This type of post is inserted within a similarly shaped socket 24, mounted in a heel such as indicated at 26, and when so inserted maintains the 35 top lift in registry with the heel at the tread end, and prevents dislodgment of the top lift due to its frictional engagement with the socket. The beveled outer ends of the resilient wings aid materially in the insertion of the yielding post 40 within the complementary socket.

It is obviously desirable in a construction of this kind where the post depends for its change in cross-section upon a fit with the socket, to definitely and uniformly size all posts during the 45 process of manufacture. This is conveniently accomplished in the assembly of the post and top lift as indicated in Figs. 6 and 7. In this operation the post is received within a cavity 30 extending from the mold cavity 32 which receives 50 the top lift. The cavity 30 is of sufficient size to loosely receive the post, which may be dropped thereto by gravity. Thereafter and before assembly with the top lift the resilient walls of the post are engaged by the opposite faces of 55

a sizing and locating plunger 34, which is moved inwardly to a fixed position to bring the walls to a predetermined position and relationship and to hold the wall 22 in contact with the wall of 5 the receiving cavity and accurately locate the post with relation to the top lift. As noted, the plunger has a V-shaped notch in the end to contact the resilient sides of the post. This sizing 10 plunger may be mounted upon the end of a slide rod 36, as indicated. In practice, after insertion of the post, the operation of the cam is initiated to bring the sizing plunger into operative relationship 15 with the post. Thereafter the top lift 42 located in the mold cavity is pressed downwardly by a plunger 44, to size the top lift and permanently assemble it with the post, the prongs 18 extending through the top lift and clinching 20 therein.

After completion of this operation, each post is reduced to an invariable size and cross-section, and properly located with respect to the top lift. This operation does not interfere with the resilient 25 characteristics of the inclined wings which upon entrance of the post into the socket exercise their function of frictionally engaging with the walls of the socket and maintaining the post therein.

30 What is claimed is:

1. The method of making a detachable top lift

construction which comprises the formation of a post of resilient cross-section, assembling the post in a loose receiving cavity, while so assembled sizing the post to a predetermined cross-section, and permanently assembling the sized 5 post with a top lift.

2. The method of making a detachable top lift construction which comprises the formation of a post of resilient cross-section, assembling the post in a loose receiving cavity, engaging the 10 post while so held by a locating member, and permanently assembling the post with the top lift while the post is engaged by the locating member.

3. The method of making a detachable top lift 15 construction which comprises the formation of a post of generally triangular and resilient cross-section, assembling the post in a loose receiving cavity, while so assembled engaging the post to locate it in a predetermined position in the cavity, and while so engaged permanently assembling the 20 post with the top lift.

4. The method of making a detachable top lift construction which comprises the formation of a post of resilient and generally triangular cross- 25 section, assembling the post in a receiving cavity, while so assembled engaging the post at two sides of the triangle to locate the post within the cavity, and while so located permanently assembling the post with the top lift.
